SUBMARINE SIGNALING

Filed Aug. 28, 1924

Inventor:
John J. Gilbert
by Edward Atty.

UNITED STATES PATENT OFFICE.

JOHN J. GILBERT, OF DOUGLASTON, NEW YORK, ASSIGNOR TO WESTERN ELECTRIC COMPANY, INCORPORATED, OF NEW YORK, N. Y., A CORPORATION OF NEW YORK.

SUBMARINE SIGNALING.

Application filed August 28, 1924. Serial No. 734,580.

This invention relates to submarine telegraph systems and more particularly to receiving equipment for such a system.

In submarine telegraph systems it is customary practice to connect the receiving apparatus between the submarine cable and a local ground or between the cable and a low resistance conductor leading to a ground at sea. By using suitable receiving equipment a maximum signal response for such an arrangement is obtained. For duplex operation however, an artificial cable so constructed as to simulate the electrical characteristics of the real cable, is connected between the receiving apparatus and the ground connection. In such a system, the signal response is materially reduced due to the added impedance of the artificial cable. Another example of sacrificing signal response in order to obtain certain desirable results is the use of a cable balancing return circuit to reduce interference local to the shore end.

The cable balancing return circuit comprises a conductor one terminal of which is located in proximity to one terminal of the main cable and the other terminal of the conductor is connected to a ground at sea through a suitable network, the impedance of the conductor, network and ground as a whole substantially balancing the impedance of the main cable. The conductor of the cable balancing return circuit may preferably be located throughout its whole length in proximity to the main cable in order that both may be equally affected by any outside source of electrical disturbance. Such a system is described in British Patent 218,261, Aug. 31, 1925.

An object of the present invention is to improve the signal response when a network having substantial impedance is connected between the receiving equipment and ground.

Another object is to improve the signal response in a submarine telegraph system employing an artificial cable or a cable balancing return circuit.

In systems heretofore known the receiving apparatus has had an input impedance for the frequency components essential to signaling of about the same magnitude as the characteristic impedance of the cable or of lower magnitude. According to the present

invention the input impedance of the receiving apparatus in duplex systems employing an artificial cable or in simplex systems employing a cable balancing return circuit, is made as high as possible in order that the signal response may be substantially the same as would be the case if a local ground were used. In a specific embodiment of the invention a three electrode electron discharge amplifier having a very high input impedance is used in connection with the high terminating impedance.

The novel features which are considered characteristic of this invention are set forth with particularity in the appended claims. The invention, both as to its organization and method of operation together with other objects and advantages thereof, will be further explained hereinafter, having reference to the accompanying drawing which shows diagrammatically a submarine telegraph system employing a cable balancing return circuit terminated in a high impedance according to this invention.

Referring now to the drawing a single core submarine cable 5 is connected to receiving equipment R by means of a twin core cable section 6 including a cable balancing return circuit. The section of cable between the lines X—X and Y—Y constitutes the twin core section including the balancing network and ground at sea. One of the twin cores 7 is connected to the core 8 of the single core cable at the line X—X while the other end is connected to the receiving apparatus R through switch 9. The other core 10 of the twin core cable 6 is connected through balancing resistance 11 to the armor wires 12 and thus to the sea water or earth at point 13. A conventional earth connection is shown in dotted lines to indicate that the resistance 11 which is connected to the armor wires shown by light lines 12 is grounded at point 13. The resistance 11 need not necessarily be connected to the armor wires 12 but may be grounded to the sea water in any suitable manner. The other end of core 10 is connected to the receiving equipment R.

The receiving equipment R comprises a vacuum tube amplifier A which may be of any suitable construction, the input circuit of which is connected through a grid polarizing battery 14 to a high impedance ele-

ment 15. The output circuit of the amplifier A is connected to any suitable recording device 16, such for example, as a siphon recorder. A condenser 20 of relatively low impedance to those frequency components essential to signaling is connected between conductor 7 and the high impedance 15 in order to prevent very low frequency earth potential variations from affecting the amplifier A. This condenser may be of the order of 50 microfarads.

A suitable arrangement for amplifier A is that shown in Fig. 6 of patent to A. M. Curtis, 1,586,970, June 1, 1926.

For transmitting purposes a transmitter T may be connected between a local ground 17 and the cable core 7 through a condenser 18 by throwing switch 9 from the position shown to switch point 19. The signaling impulses are thus transmitted by way of the local ground instead of the ground at sea through core 10 and resistance 11. The same type of transmitting equipment is provided at the distant end of the cable for transmitting purposes and therefore has not been shown.

Signaling takes place in the well known manner. Code impulses are impressed upon the cable at the sending end and the received impulses are amplified in amplifier A and shaped by suitable networks before being recorded by recording device 16.

As is pointed out in applicant's copending application, Serial No. 648,690, supra, the advantages of the use of the cable balancing return circuit are due to the fact that the interfering currents are reduced to a much greater degree than the signal response. By the arrangement of the present invention the signal response is substantially unchanged by the introduction of the ground at sea with a resulting greater advantage in favor of the latter. This advantage may be expressed by saying that the high impedance termination for frequency components essential to signaling makes possible a more favorable ratio of signal strength to "out of balance" interference.

An explanation for the improved results due to the high impedance termination of the cable and balancing return circuit can probably best be given mathematically. Such an explanation will now be given.

Let γ , k and a be respectively the propagation constant, characteristic impedance and length of the single core cable; and γ' , k' and b be the corresponding quantities for the twin core between the ground at sea and the terminal. The impedance of the submerged artificial line will then be k .

Let V_o and I_o be the voltage and current impressed at the distant terminal and let V_T and I_T be the voltage and current at the receiving apparatus, which has an impedance Z_T as seen from the cable. Then it can be shown that

$$V_T = V_o \left[\frac{KC' - k'S'}{k(S+C) + KC} \right] \quad (1)$$

$$I_T = \frac{V_o}{k'} \left[\frac{k'C' - KS'}{k(S+C) + KC} \right]$$

where

$$\begin{aligned} C &= \cosh \gamma a & S &= \sinh \gamma a \\ C' &= \cosh \gamma' b & S' &= \sinh \gamma' b \end{aligned}$$

and

$$K = \frac{k'S' + Z_T C'}{k'C' + Z_T S'} k'.$$

We can assume for the present purpose

$$k' = 2k \text{ and } \gamma' = \gamma.$$

Three special cases are of particular interest in showing what effect the value of Z_T has upon the efficiency of reception.

Case 1.— $Z_T = 2k$.

That is, the terminal impedance is made equal to the characteristic impedance of the twin core cable. This is a condition that gives maximum energy of the received signal and is the condition that is ordinarily approximated in submarine cable operation. Placing this value of Z_T in the above formulae we get

$$V_T = V_o e^{[\gamma(a+b)]}$$

and

$$I_T = \frac{V_o}{2k} e^{[\gamma(a+b)]}.$$

The received voltage is thus exactly the same as if the ground at sea were absent and the main cable were terminated in a network having an impedance equal to the characteristic impedance k . The current, however, according to (2) is only half the value that would be obtained if the cable balancing return circuit were not employed, thus the effect of the return circuit in this case is to reduce the maximum energy that can be received to one-half the value that can be received where the sea earth is not used.

Case 2.— $Z_T = 0$.

This represents the case where the terminal impedance is made very small compared with the characteristic impedance of the cable, which arrangement would be employed if it were desired to obtain large currents from the cable at the expense of the voltage. From formula (1) we see that in this case

$$\begin{aligned} V_T &= 0 \text{ and} \\ I_T &= \frac{V_o}{k} e^{[\gamma(a+b)]}. \end{aligned} \quad (3)$$

The current is thus only one-half the value that would be obtained by use of a low im-

pedance termination between the main cable and ground.

Case 3.— $Z_T = \infty$.

This represents the case where the impedance of the receiving apparatus is very large compared with the characteristic impedance of the twin core cable. We have for this case

$$10 \quad V_T = 2V_o e^{[\gamma(a+b)]} \quad (4)$$

and $I_T = 0$.

The received voltage in this case is thus exactly equal to the voltage obtained between the main cable and ground on open circuit, which is the best condition for operation where voltage amplification is employed. The ground at sea in this case does not reduce the efficiency of transmission.

From the preceding it is obvious that in designing terminal apparatus to be used in connection with a submarine cable and cable balancing return circuit it is desirable to make the impedance of the receiving network large compared with the characteristic impedance, or more generally, the input impedance of the twin core cable for the frequencies for which as large an amplitude as possible is desirable. These frequencies will lie in the range between the signaling frequency and a value about 1.5 times the signaling frequency.

From the above explanation it is evident that best results would be obtained if the terminal impedance could be made infinite. This is physically impossible in any material installation but this ideal relationship can be approximated. In one embodiment of the invention the impedance of the receiving equipment to the frequency components essential to signaling has been made as high as 3,000 to 6,000 ohms, as compared with 800 ohms for the characteristic imped-

ance of the cable with balancing return circuit. The reduction in signal response due to the return circuit was practically negligible. From this it follows that the impedance of the terminal apparatus should be four times or more the magnitude of the characteristic impedance of the cable and balanced sea earth.

It is to be understood that embodiments of the invention other than the one illustrated in the drawing are possible without departing from the spirit of the invention as defined in the appended claims.

The expression "long submarine cable" is employed in the claims to indicate a submarine cable of such length that in the major portion of the cable the magnitude of the signaling current is substantially independent of the magnitude of the receiver impedance facing the cable.

What is claimed is:

1. In a submarine telegraph system, a long submarine cable, a cable balancing sea earth return circuit having a terminating impedance at its sea end approximately equal to the characteristic impedance of said cable, said return circuit having an impedance substantially equal to the input impedance of said submarine cable, and a receiver the input impedance of which is at least three times the input impedance of said cable and return circuit combined.

2. In a submarine telegraph system, a long submarine cable having a characteristic impedance of approximately 400 ohms, a cable balancing sea earth return circuit having an impedance substantially equal to the characteristic impedance of said submarine cable, and a receiver the input impedance of which is at least 3,000 ohms.

In witness whereof, I hereunto subscribe my name this 26th day of August A. D., 1924.

JOHN J. GILBERT.
